UNITED STATES PATENT OFFICE.

CLARENCE W. BENNETT, OF NEW YORK, N. Y.

STEERING HEAD FOR VELOCIPEDES.

Application filed March 8, 1921. Serial No. 450,726.

To all whom it may concern:

Be it known that I, CLARENCE W. BENNETT, a citizen of the United States, residing at 114 West 79th Street, New York, in the county of New York and State of New York, have invented certain new and useful Improvements in Steering Heads for Velocipedes, of which the following is a specification.

10 This invention relates to an improved steering head for a child's velocipede and has reference more particularly to the construction and design of such a steering head which may be cast in one piece of material.

15 The invention has for its main object to improve and simplify the construction of steering heads now used to unite and control the steering mechanism of a velocipede.

20 In the construction of steering heads of this character, it is a well known expedient to provide a built up device comprising several members united to form a compact steering unit, but it has also been found that the number of parts and the cost of assembling 25 them involves considerable expense. In order to overcome this objection the present invention contemplates the provision of a steering head constructed of one piece of material, cast in approximately its proper 30 shape, and capable of being employed to couple the main frame and the steering fork of a velocipede without sacrificing either strength or durability.

35 A further object of this invention is the provision of means included in the design of the steering head whereby the stem of the handle-bar support may be used as the steering post.

40 The invention consists in the features and combination of elements hereinafter fully described with reference to the accompanying drawings, wherein

45 Fig. 1 is a perspective view of a velocipede having the one piece steering head incorporated therein.

Fig. 2 is a substantially vertical sectional view on an enlarged scale showing the relative position of the steering head, side frame and steering post.

50 Fig. 3 is a sectional view taken on the line 3-3 of Fig. 2.

Fig. 4 is a perspective view of the one piece steering head before the fork blades have been attached thereto.

55 Fig. 5 is a substantially vertical sectional

view of a slightly modified form of the steering head and the steering post which is used as the fulcrum for the steering mechanism.

Referring to the drawing 10 denotes the two downwardly and rearwardly extending 60 side pieces having suitable members at their lower ends adapted to receive the rear axle 11 supported upon the wheels 12. A seat 13 is supported between the inner sides of the side pieces 10 and may be of any of the well 65 known types now in use. The opposite ends of the side pieces 10 are connected with a sleeve 14 having its ends folded together in flat engagement, as shown at 15, and provided with a tubular portion 16 adapted to 70 receive the steering post in the usual manner.

The tubular portion 16, before referred to, is partially embraced by a steering head 17 in such a manner that an arcuate movement of 180 degrees is possible for the sleeve 14. 75 This is accomplished by providing the cylindrical portion of the steering head with an open side 18 of sufficient height to loosely embrace the tubular portion 16 and to permit the central openings 19 in the upper and 80 lower walls 20 and 21 respectively, to register with the bore of the portion 16. A steering post 24, the latter in the present instance being the stem of the handle-bar support 25, is adapted to be inserted into the upper opening 19 and through the bore of the sleeve 14 into the lower opening 19. The stem or steering post 24 may be sufficiently long to project considerably beyond the under face 85 of the wall 21 to provide room for vertical 90 adjustment. In the preferred form of the invention a set screw 26' is carried by the upper wall 20 and is adapted to bear against the adjacent surface of the steering post 24 so that the latter when rotated will also 95 move the steering head 17. Depending from the lower wall 21 are two diverging arms 26.

The fork members 27 are suitably secured at their upper ends as for instance by means of rivets, to the depending arms 26 and are supported at their opposite ends by the front wheel 28.

In Fig. 5 the steering head 17 has been slightly modified to include a lug 29 depending from the under side of the lower wall 21 105 adjacent the central opening 19 therein and provided with a transversely disposed opening 30. The diameter of the end of the steering post 24 is reduced, as at 31, to provide a shoulder 32 thereon, adapted to seat against 110

the inner face of the wall 21. In this construction the opening 19 in the wall 21 is of smaller diameter than the opening 19 in the upper wall 20. The portion 31 of the steering post 24 is provided with counter openings 32' which may be registered with the opening 30 by moving the post 24 axially. A cotter pin 33 may be introduced into the opening 30 and into the opening 32' brought 10 in register with the former.

In the assembling of the present steering head, sleeve 14 and handle-bar support stem 24, to provide an efficiently operated steering mechanism for a velocipede, it will be assumed that the side pieces 10 have been properly riveted together about the portion 15 of the sleeve 14; and the fork members have been secured to the depending arms 26 as before described. The several elements of the 20 velocipede should then be ready to be assembled as follows:

Tubular portion 16 is inserted into the opening 18 until the bore of the former is in register with the openings 19 in the walls 20 25 and 21 respectively. The stem 24 is then inserted into this opening until the desired height required for the handle-bars has been reached, whereupon the set screw 26' is tightened down against the stem 24 as shown in 30 Fig. 2.

It will be obvious that in both forms of the invention the height of the steering bars may be readily adjusted. In the preferred form shown in Figs. 1 to 4, adjustment is effected by loosening screw 26', moving the steering post up or down to the desired position and then again tightening screw 26'. In the modified form the cotter pin 33 is withdrawn, the post raised or lowered and after the desired height adjustment has been effected the cotter pin is inserted into the appropriate opening 32'.

I claim:

In a velocipede, the combination with a frame having a tubular portion, of a steering head comprising a member having a recessed lateral wall and end walls provided with aligned openings, the end wall of said steering head being adapted to embrace the ends of the tubular portion of the said frame, 45 and a steering post adjustable in said aligned openings of the end walls of the steering head and tubular portion of the frame, the said steering post being adapted to be rotated with the steering head and having the 50 tubular portion of the frame as a bearing therefor.

In testimony whereof I affix my signature.

CLARENCE W. BENNETT.
